TOY SUBMARINE

Edward A. Buehler, Troy Township, Oakland County, Mich., assignor of one-tenth to McConnell-Petermann Co., Inc., a corporation of Michigan

Application February 26, 1940, Serial No. 320,868

5 Claims. (Cl. 46—94)

This invention relates to certain new and useful improvements in toy submarines.

The principal objects of this invention are:

5 First, to provide a submersible aquatic toy of simple, durable and inexpensive construction;

Second, to provide such a toy having a minimum number of parts wherein each of the component parts is of simple construction;

Third, to provide such a toy which cannot easily 10 be put out of working order;

Fourth, to provide such a toy employing a rubber band method of propulsive power but simplifying the suspension and operative action thereof;

15 Fifth, to provide such a toy which is designed not only to submerge but travel upon the surface of the water according to the wish of the operator;

Sixth, to provide in such a toy a simple mechanism to control its action, said mechanism being 20 transversely inserted and secured in the prow of such toy;

Seventh, to provide an inexpensive system of ballast for such a toy which may be pumped into the hull interior; and

25 Eighth, to provide such a toy having such other advantages as shall hereinafter appear.

With the foregoing objects in view, this invention consists of the combination and arrangement of its parts as is hereinafter more fully described, 30 as illustrated in the accompanying drawing, and as set forth in the claims therefor.

In the accompanying drawing, consisting of one sheet, forming a part hereof:

Fig. 1 is a perspective view of this invention.

35 Fig. 2 is a longitudinal section of Fig. 1.

Fig. 3 is a sectional view on line 3—3 of Fig. 1.

Fig. 4 is a rear elevational view of Fig. 1.

Fig. 5 is a sectional view on line 5—5 of Fig. 1.

Fig. 6 is a perspective view of directional fin 40 when adjusted for submerging of submarine.

Fig. 7 is a perspective view of directional fin when adjusted to confine movement of the submarine to the surface of the water.

Referring more particularly to the drawing, 45 the hull consists of two complementary sections 1 and 2 and, when secured together, simulate the general appearance of a submarine. Section 1 forms the starboard side of the vessel and section 2, the port side. The sections 1 and 2 are secured together by folding and crimping extending portions of said sections 1 and 2 and form a hull substantially circular at the point of its greatest diameter, as shown in Fig. 3, and tapering fore and aft therefrom, as shown in Figs. 1 and 2.

50 In order to further simulate the appearance of

a submarine, a simulated gun 12, a simulated tower 13, and a simulated periscope 14 extend upward from the hull as shown in Figs. 1 and 2. In order to keep the vessel from listing and to maintain it in an upright position, a ballast 3 5 consisting of a concrete or Portland cement mixture, or other suitable mixture, is injected into the hull and permitted to harden in the desired position, as shown in Figs. 2 and 3.

To further simulate the appearance of a submarine, simulated torpedo tube openings 15 are provided by indentation of the fore portion of the vessel, there being four of such simulated torpedo tube openings 15, as shown in Fig. 4.

The propulsive power is supplied by means of 15 an ordinary rubber band 8, one extremity of which is affixed to a hook 9 extending astern from the fore closure or directional fin retention means 10 secured in the prow of the vessel and the other extremity to a hook 7 extending forward from the stern closure 6.

20 Hook 7 performs a dual function, its shank serving as an axle or shaft for the propeller 4. The propeller 4 is held in position by means of a washer 5 abutting the rearward extremity of the 25 stern closure 6. This construction of the propeller assembly is shown in detail in Fig. 5. The propeller 4 also performs a dual function, being used as a key to wind the propulsive power means, 30 rubber band 8.

The directional fin 11 consists of a quite substantially square or oblong piece of sheet metal with its central area slightly dented or depressed to permit its being snapped upward or downward from true horizontal by the pressure of the hand 35 or finger of the operator. Directional fin 11, shown in Fig. 6 snapped down, causes the vessel to dive or submerge when in this downward position. When directional fin 11 is snapped upward to a point which is slightly above true horizontal, Fig. 7, the vessel follows the surface of the water.

The directional fin 11 is secured to the prow of the vessel by means of the fore closure or directional fin retention means 10, being inserted 45 in a recess of the fore closure means 10 and secured in a traverse position in relation to the prow, as shown in Fig. 4.

In the preferred embodiment of this invention 50 it is contemplated that hull sections 1 and 2, extending simulated gun 12, simulated tower 13, and simulated periscope 14 will be stamped of metal or other moldable material; and that the directional fin retention means or fore closure 10 55

and the stern closure **6** will be made of wood, rubber, or other suitable material.

The toy submarine assembly is put in operation by simply adjusting the directional fin **11** for the desired control, winding propulsive power means **8** with propeller **4**, and launching the toy in the water.

It is realized that the rubber band method of providing propulsive power is not new but a simplified application is herein accomplished with reference to the arrangement of the means of suspension provided solely within the interior of the vessel.

What I claim is:

1. In a toy submarine, a frontal control means, substantially as described, for causing such a miniature vessel to submerge or follow the water's surface comprising an oblong or square piece of sheet metal, slightly dented in its central area, secured transversely in relation to the prow of such vessel within a retention means therefor.

2. In a toy submarine, a directional fin retention means comprising a fore closure means with its bow extremity recessed by receive and secure transversely in relation to the prow of such vessel a flat oblong or square directional fin and having a hook extending astern from its rear extremity.

3. In a toy submarine, a directional fin consisting of an oblong or square piece of sheet metal having its central area dented, which is

adjustable by the application of pressure to points above and below true horizontal, substantially as described.

4. A toy submarine substantially as described, comprising a hull simulating the appearance of a submarine with extending simulated gun, tower, and periscope, a ballast substance within said hull, a propulsive power means suspended entirely within the hull interior by attachment to two hooks secured in opposing relation by means of stern and fore closure means affixed in apertures fore and aft in said hull, a propeller, and a flat oblong or square directional fin slightly dented in its central area and secured transversely in relation to the prow of said vessel with- 15 in said fore closure means.

5. A toy submarine substantially as described, comprising a hull simulating the appearance of a submarine, a ballast means therein, a propulsive power means suspended entirely within the hull 20 interior, a stern closure means housing within its longitudinal center a shaft having at its stern extremity a combination propeller-key and having at its fore extremity a hook, a fore closure means having at its stern extremity a hook and 25 having at its fore extremity a transverse recess, and a flat oblong or square directional fin slightly dented in its central area transversely secured in relation to the prow of said vessel within said transverse recess of the said fore closure means. 30

EDWARD A. BUEHLER.
